ABSTRACT OF THE DISCLOSURE

A fluid permeable conduit is positioned within a second conduit and separated therefrom by helically inclined vane members, forming two separate helically shaped fluid passageways. A heating fluid is introduced into one passageway under elevated pressure, while the pressure in the other passageway is reduced. The yarn to be heated is passed through the fluid permeable conduit.

This invention relates to method and apparatus for heating yarn.

In conventional yarn heating tubes, air enters the tube with the yarn and moves through the tube either concurrently or countercurrently with the yarn, while the wall of the tube indirectly heats the yarn. The presence of the air in the yarn seriously reduces the heating capacity of the device, while the passage of the air from one end of the tube to the other carries condensation and other contaminants from one section of the yarn to another section.

It has now been discovered that these difficulties can be avoided by subjecting one side of each axial segment of yarn in an elongated zone with a heating fluid while reducing the pressure on the opposite side of each axial segment, and continuously varying the direction of the resulting differential pressure with respect to the axis of the yarn as each segment of yarn passes through the zone. This can be accomplished by the use of a fluid permeable conduit surrounded by a second conduit and connected thereto by helical vanes to form two spiraling passageways. A heating fluid can be supplied to one passageway at elevated pressure, while the pressure in the other passageway is reduced.

Accordingly, it is an object of the invention to provide an improved method and apparatus for heating yarn. Another object of the invention is to rapidly remove contaminants from a yarn. Another object of the invention is to increase the heat transfer rate in a yarn heating device. Yet another object of the invention is to increase the yarn throughput for a yarn heating device.

Other objects, aspects and advantages of the invention will be apparent from a study of the specification, the drawing and the appended claims to the invention.

In the drawings, FIG. 1 is an elevational view in cross section of a yarn heating device in accordance with a presently preferred embodiment of the invention, and FIG. 2 is a cross-sectional view along line 2—2 of FIG. 1.

Referring now to the drawings in detail, heating device 10 comprises a tubular conduit 11 positioned within larger tubular conduit 12 and extending generally parallel thereto, preferably coaxially therewith. An annular closure plate 13 extends from one end of conduit 12 to the outer wall of conduit 11 to close the opening therebetween. Similarly, an annular closure plate 14 extends from the other end of conduit 12 to the outer wall of conduit 11 to close the opening therebetween, thereby defining an enclosed annular chamber. Helically inclined vane members 15 and 16 are positioned in the annular chamber and are axially spaced apart from each other. Vane members 15 and 16 extend axially from closure plate 13 to closure plate 14 and laterally from the outer wall of conduit 11

2

to the inner wall of conduit 12, to form two separate helically shaped fluid passageways 17 and 18. Conduit 11 is formed of a porous material, for example a sintered metal, to provide a plurality of fluid passageways in the wall thereof spaced along the length thereof which permit fluid communication between passageways 17 and 18 and the adjacent interior 31 of conduit 11.

Conduit 21 connects one end of passageway 18 to a vacuum pump 22 or other means of reducing the pressure in passageway 18 substantially below the fluid pressure in the interior of conduit 11. Conduit 23 connects one end of passageway 17 to a source 24 of heating fluid at a pressure above the fluid pressure in the interior of conduit 11. If desired an outlet conduit 20 can be provided at the other end of passageway 17 to remove unused heating fluid. Any suitable heating fluid can be employed, but steam is presently preferred in most instances because of its economics and heat transfer rate. In the presently preferred embodiment illustrated in the drawing, conduits 21 and 22 are positioned adjacent the yarn inlet end of conduit 11, but it is within the contemplation of the invention for these connections to be adjacent the yarn outlet end or at an intermediate point or points. A sleeve 25 of a suitable insulating material surrounds all or a major portion of conduit 12 to prevent condensation in passageway 17. Nip rolls 26 and 27 can be provided to pass the yarn 30 into the heating device 10. Nip rolls 28 and 29 can be utilized at the outlet end of device 10 in addition to or in lieu of the utilization of nip rolls 26 and 27. Rolls 28 and 29 can be positioned around the outlet end of conduit 11 and driven at a slower speed than rolls 26 and 27 which can be positioned adjacent the inlet of conduit 11 to thereby form a stuffer crimper.

In any plane cut through the annular chamber in heating device 10 perpendicularly to the axis of conduit 11, one example being illustrated in FIG. 2, steam from passageway 17 will be entering passageway 31 of conduit 11 through approximately one half of the wall of conduit 11 and spent steam, air and any condensate will be exiting passageway 31 through the other half of the wall conduit 11 into passageway 18. Substantially all of the steam transverses passageway 31 and is withdrawn into the opposite section of passageway 18, while the remainder of the steam passes into the superadjacent or subadjacent section of passageway 18. The direction of the steam flow across passageway 31 changes along the length of passageway 31 in a spiraling fashion. The application of steam to one side of an axial segment of the yarn and the effectuation of the reduced pressure on the opposite side of the axial segment of yarn promotes a continuous flow of fresh steam laterally through the axial segment of yarn. The constantly changing direction of the steam flow which the axial segment of yarn experiences as it travels through passageway 31 eliminates stagnant areas or eddies within the yarn, thereby continuously exposing all of the yarn to fresh steam, and prevents the yarn from being packed against one wall of passageway 31.

The reduced pressure in passageway 18 maintains the transverse flow rather than permitting the heating fluid to pass the length of conduit 11 with the yarn 30. The transverse motion of the heating fluid with respect to the yarn not only continuously exposes each axial segment of the yarn to fresh heating fluid, but also achieves a rapid removal of any condensate or other contaminants from the yarn. The removal of air from the yarn entering conduit 11 permits a greater degree of direct contact between the yarn and the heating fluid, resulting in a faster heat transfer rate. This permits the usage of a shorter tube for a given yarn throughput or an increased yarn throughput for a given length of heating tube.

While conduit 11 is preferably made of sintered metal, it is possible to utilize a nonporous metal conduit which

has a plurality of orifices drilled or punched therein. Such orifices could be distributed substantially uniformly throughout the length of conduit 11 or in a varying pattern, as desired. While nip rolls have been illustrated as the yarn conveying means, other devices can be employed, for example, fluid jets. The term "yarn," as used herein, includes textured or untextured filaments of natural or synthetic material, in the form of staple or continuous filaments, or combinations thereof. A single continuous filament or a bundle of continuous and/or staple filaments can be processed in the device of the invention. The bundle can range from two filaments of small denier per filament to a tow having a total denier of 100,000 or more.

Reasonable variations and modifications are possible within the scope of the foregoing disclosure, the drawing and the appended claims to the invention.

I claim:

1. Apparatus comprising first and second tubular conduits, said first conduit being positioned inside said second conduit and extending at least approximately parallel thereto, first closure means extending from one end of said second conduit to said first conduit to close the opening therebetween, a second closure means extending from the other end of said second conduit to said first conduit to close the opening therebetween, first and second axially spaced apart substantially helically inclined vane members extending axially from said first closure means to said second closure means and extending laterally from the outside wall of said first conduit to the inside wall of said second conduit to form two separate substantially helically shaped fluid passageways, said first conduit having a plurality of fluid passageways in the wall thereof spaced along the length thereof to provide fluid communication between said first and second fluid passageways and the adjacent interior of said first conduit, means for reducing the pressure in said first fluid passageway substantially below the fluid pressure in the interior of said first conduit, means for introducing into said second fluid passageway a heating fluid at a higher pressure than the fluid pressure in the interior of said first conduit, and means for passing a yarn through said first conduit.

2. Apparatus in accordance with claim 1 wherein said first and second tubular conduits are coaxial.

3. Apparatus in accordance with claim 1 wherein said first conduit is formed of sintered metal.

4. Apparatus in accordance with claim 1 wherein said means for reducing the pressure comprises a vacuum pump.

5. Apparatus in accordance with claim 1 wherein said means for passing a yarn through said first conduit comprises a pair of nip rolls mounted adjacent the inlet end of said first conduit.

10 6. Apparatus in accordance with claim 1 further comprising an insulating sleeve positioned around said second conduit.

15 7. A process for heating yarn which comprises passing said yarn through an elongated zone, subjecting one side of each axial segment of yarn in said zone to a reduced fluid pressure and subjecting the opposite side of each said axial segment of yarn in said zone to a heating fluid at an elevated pressure to establish a pressure differential across each said axial segment of yarn in said zone, and continuously varying the alignment of said pressure differential with respect to the axis of the respective axial segment of yarn in said zone as each axial segment of yarn passes through said zone to thereby alternately subject each portion of yarn to a reduced fluid pressure and to heating fluid at elevated pressure.

20 8. A process in accordance with claim 7 wherein said heating fluid is steam.

25 9. A process in accordance with claim 7 wherein said step of continuously varying the alignment of said pressure differential comprises varying said alignment in a helical manner along the axis of said zone.
